ROTARY AIR MOTOR

August C. Ripke, Austin, Minn.

Application June 2, 1937, Serial No. 146,028

2 Claims. (Cl. 121—78)

This invention has relation to a mechanical device for transforming power as for instance compressed air into rotary motion and/or vice versa.

5 An object of the invention is to provide a transmission assembly that can be built strong and compact and at relatively low cost, avoiding extraneous and unnecessary parts as far as possible.

10 A further object of the invention is to provide an improved structure of what may be alternatively an air motor or air compressor in the form of a piston, on the periphery of a revolvable disk, that travels in a tubular stator.

15 A further object of the invention is to provide an air motor with a piston revolving in an annular tube or cylinder with a knife valve between its inlet and outlet ports that swings out of the way to allow the piston to pass.

20 A still further object of the invention is the provision of a device of the nature and for the purpose set forth that is characterized by structural simplicity, durability and efficiency being thereby rendered commercially desirable.

25 To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure 35 wherein like characters indicate like parts throughout the several views.

In the drawings:

Figure 1 is a side elevation of the device;

Figure 2 is a transverse section of the air

40 motor;

Figure 3 is a front elevation of the revolving transmission; and

Figure 4 is a sectional detail of the air motor valve.

45 The air motor comprises an annular hollow tube-like stator casing 1 with an open slot 2 at its inner circumferential median to accommodate a revolvable disk 3. The periphery of this disk 3 enters the tube through the slot 2 and

50 these related parts are air sealed as found best in practice, a cross-head flange 6 on the disk being here shown. The purpose of the disk is to support the piston 7 that is caused to revolve in the tubular stator's race-way under propulsion of compressed air entering through the port

8 while pressure ahead of the piston finds outlet through the port 9. A laterally swinging knife valve or abutment 10, pivoted on the base 11, is enclosed in the housing 12 and operates through a slot 13 in the side wall of the tube 1 to divide 5 the inlet and outlet ports 8 and 9 and swing out of the path of the piston 7 to let it pass. This valve or abutment 10 has an outline corresponding with the interior cross section of the tubular raceway of the stator 1 when the flange 6 of the 10 rotor disk 3 is disposed therein; the said cross-head flange 6 having its periphery transversely describing the arc in which said valve or abutment 10 swings.

The mechanical transformer or transmission 15 consists of a fixed horizontal shaft 15 supported on a pair of spaced standards 16, 16'. A gear-wheel 17 is keyed to this shaft and on it revolve a pair of diametrically opposite gears 18, 18' of similar diameter. Each gear 18, 18' has an axial 20 shaft 19, 19' projecting forwardly in one case and rearwardly in the other. On the outer end of the shaft 19, 19' is a chain sprocket 20, 20' connecting by an endless chain 21, 21' with a like sprocket 22, 22' rotatable on the fixed shaft 15. 25

A revolvable framework 23 turns on the fixed shaft 15, comprising four diametric arms 24 spaced on opposite sides of the gear-wheel 17 and connecting the shafts 19, 19' of the planetary gears 18, 18'. These arms 24 are united by 30 cross pieces 25 at opposite ends.

An offset coupler 26 connects the disk 3, axially aligned with the shaft 15, with the front gear chain sprocket 22, while to the rear chain sprocket 22', on the fixed axle 15, an offset power 35 wheel 27 is attached.

In use, it will be seen that as pressure is fed to the stator tube 1 by the inlet port 8, the piston carrying disk 3 will be made to revolve carrying with it the front chain sprocket 22, that 40 by the chain 21 turns the sprocket 20, its axle 19 and the planetary gear 18 thereon causing the same, and the associated framework 23, to travel around the fixed gear wheel 17. The diametrically opposite planetary gear 18' travels in 45 unison and in doing so turns its shaft 19' and chain sprocket 20' that by the rear chain 21' rotates the gear chain sprocket 22' and its offset power-wheel 27 off which latter the power is taken. 50

From the foregoing description taken in connection with the accompanying drawings, it will be manifest that a mechanical device for transforming power is provided that will fulfill all the necessary requirements of such a device but as 55

- many changes could be made in the above description and many apparently widely different embodiments of the invention may be constructed within the scope of the appended claims without departing from the spirit or scope thereof, it is intended that all matters contained in the said accompanying specification and drawings shall be interpreted as illustrative and not in a limitative or restrictive sense.
- 10 What I claim as new is:
1. An air motor comprising an annular, hollow, tube-like stator casing; an open slot at the inner circumferential median thereof; a revolvable disc with its periphery entering said tube through said slot; a cross-head flange on the periphery of said disc inside said tube-like stator casing providing an air seal therefor; a piston

carried on said disc and revolvable in said tube-like stator; inlet and outlet ports in said stator; and a swinging abutment therebetween adapted to swing clear to pass said piston, said swinging abutment corresponding in outline with the interior of said tube-like stator casing with the rotor flange therein and said flange on its periphery describing the arc in which said abutment swings.

2. In combination with claim 1, a means for 10 operating said swinging abutment, comprising a cam laterally offset from said disk and a push rod pivotally attached to said swinging abutment and normally held spring-pressed against said cam.

AUGUST C. RIPKE.
